ATTORNEY.

UNITED STATES PATENT OFFICE.

FRANCOIS D. RAYMOND, OF FALL RIVER, MASSACHUSETTS.

LOOM.

1,152,905.

Specification of Letters Patent.

Patented Sept. 7, 1915.

Application filed November 28, 1914. Serial No. 874,539.

To all whom it may concern:

Be it known that I, FRANCOIS D. RAYMOND, a subject of George V, King of Great Britain, residing at Fall River, county of Bristol, Commonwealth of Massachusetts, have invented certain new and useful Improvements in Looms, of which the following is a specification.

This invention relates to weaving and particularly to a warp change mechanism for a loom.

My present invention contemplates the simultaneous removal of the warp rest and its stop motion detectors from the warp stop motion frame when it is desired to substitute a new warp or to temporarily lay aside the warp in the loom. This has been heretofore attempted but the detectors or "wires" are liable to become mixed or crossed and it has been necessary to carefully tie the sets to prevent crossing or breaking the warp.

My invention has made a very considerable saving in the time of the loom tender as well as relieving the loom fixer and also a saving of material and labor in damaged warps and spoiled cloth.

My warp change mechanism may be adapted for use with either mechanical or electrical stop motions. For the purposes of the patent however, I have shown it in connection with a conventional mechanical stop motion of the type wherein the detectors are thin flat metallic strips or "wires" having closed slots for the reception of the supporting bars.

The construction and operation of my device will be more fully disclosed in the specification that follows and in the drawings forming a part of that specification I have shown as an illustrative embodiment a warp change which not only clearly illustrates my invention but is in itself a form proven to be satisfactory in practice and well adapted to manufacture.

Throughout specification and drawings like reference numerals are correspondingly applied and in these drawings, Figure 1 is a front elevation of my warp change mechanism, Figs. 2 and 3 are detail sections on

the lines 2-2 and 3-3 respectively of Fig. 50 1, and Fig. 4 is an end elevation.

In order to make my device applicable to almost any of the standard looms now in use I provide end castings 7 which may be adjustably mounted on the frame. Each end casting has a socket 8 with set screws 9 providing for an adjustable mounting on brackets or rods as 10 secured to some fixed part of the loom.

Each casting 7 has a recess 7¹ upon its inner face to receive the end plates 11 of the warp change. Adjacent the lower ends of these recesses the castings 7 have each a pair of lugs to which are rigidly secured a pair of parallel bars 12 providing the back stops. Journaled in the lower ends of the castings and in an intermediate bearing depending from the back stops in the form of a yoke 13 is a rock shaft 14 having arms 15 to which is secured a feeler blade 16 which oscillates between the back stop bars 12 and is limited in its movements by the curved sides of the yoke 13. Beyond the end casting 7 at the right (Fig. 1) the rock shaft 14 has a rocker arm 16¹ adapted for contact by some moving part of the loom whereby to oscillate the rock shaft 14 against the tension of its spring 17. The spring 17 is fastened at one end to the opposite end of the rock shaft beyond the casting 7 at the left (Fig. 1) and at its other end to an eye on the outer face of said casting. The spring returns the rock shaft to initial position after each actuation thereof.

The warp change is in the form of a plurality of bars mounted in the end plates 11 which have been referred to hereinabove as being removably received in the recesses of the casting 7. In the drawings, I have shown these bars as being five in number although this number may obviously be varied. The three lower bars 18 constitute the warp rests over which the warp threads are drawn and kept separated by the sets of "wires" 20 in which the warps have been threaded. The two upper bars 19 constitute the supports for the banks or series of gravity detectors or "wires" 20. These detec-

tors may conveniently be in the form of thin flat metallic strips having closed slots 21 for the reception of the guiding and supporting bars 19 and warp eyes 22 for the 5 reception of the warp threads.

The warp change frame with its detectors is bodily removable from the warp stop motion frame by simply releasing a latching device which normally locks it in the 10 loom. This latching device consists of a pair of slotted attaching members 23 adjustably held to the back stop rods 12 by screws 24. The members 23 have each spaced ears connected by pins 25 on which 15 is rigidly mounted a cross piece 26. The cross piece 26 is slotted in the direction of length of the warp rest bars 18 to receive the bottom edges of said bars. The slotting of the cross piece provides a plurality of 20 upright lugs 27 between which the warp rest bars 18 loosely lie.

Pivoted on one of the pins 25 is a link 28 having a laterally projecting swiveled ear 29 in which is swiveled the stud of a locking 25 piece 30. When the piece 30 is in locking position, it is disposed across the warp change between the bars 18 and 19. The bottom edge of the cross piece 30 is slotted as indicated at 31 at points opposite the 30 slots of the cross piece 26 to receive the upper edges of the warp rest bars 18. The upper edge of the cross piece 30 is slotted as indicated at 32 to receive the bottom edges of the detector supporting bars 19. The 35 cross piece 30 has a laterally projecting lug 33 which is received in a recess 34 in a co-operating keeper member 35 pivoted on the pin 25 of the opposite attaching member 23 of the latching device.

40 The keeper 35 has an inwardly projecting lug 36 provided with a toe piece 37 which cooperates with one of the upright spacing lugs formed by the slots 32 of the cross piece 30 to lock one of the detector bars 19. The 45 keeper member 35 also has a threaded stem 38 on which a thumb nut 39 is threaded.

The thumb nut 39 cooperates with the forked end 40 of a top latch piece 41 pivoted to the free end of the link 28. This 50 latch piece is slotted along its bottom edge as indicated at 42 opposite to the slots of the cross piece 30 to engage the upper edges of the detector bars 19.

In use, the warp change is filled and inserted in the recesses of the castings 7 and locked therein by the latching device. When a warp thread breaks or develops an 55 undue slackness, its detector drops and contacts the feeler blade which through suitable stop mechanism (not shown) stops the loom.

When all the warp threads in the stop motion frame have been woven, the warp change is removed by unlatching the keeper

and lifting the warp rest bars and detector 65 bars with their banks of detectors intact from the loom. Another frame which has already been filled in the filling room is then placed in the loom and latched, and the original frame is returned to the filling 70 room for refilling. The "wires" 20 are thus kept in their proper place and the drawing in of the new warp quickly and correctly done without danger of mistake or mishap.

Various modifications in the form and 75 construction of my device may obviously be resorted to within the limits of the appended claims.

What I therefore claim and desire to secure by Letters Patent is:—

1. In a warp stop motion, a frame, a warp change mechanism removably mounted in said frame and including a pair of spaced warp rest bars and a detector supporting bar, and a latching device for removably locking said warp change mechanism in said frame and including a fixed latch piece having engagement with said warp rest bars, a swiveled latch piece having engagement with said warp rest bars and with said detector supporting bar, and a pivoted lockable member having engagement with said detector supporting bar, and means for locking said pivoted member.

2. A latching device for removably locking the warp rest and detector supporting bars of a warp stop motion for a loom, comprising a pair of attaching members, a cross piece fixed to said members and having engagement with the lower edges of the warp rest bars, a pair of lateral members pivoted to said attaching members, a latch member swiveled to one of said lateral members and disposed for engagement with both the warp rest and the detector supporting bars, and a latch member pivoted to one of said lateral members, above the swiveled member and disposed for engagement with said detector supporting bars and for locking engagement with the co-operating pivoted lateral member.

3. A latching device for removably locking the warp rest and detector supporting bars of a warp stop motion for a loom, comprising a pair of adjustable attaching members, a cross piece fixed to said members and having a plurality of locking projections disposed for engagement with the lower edges of the warp rest bars, a pair of lateral members pivoted to said attaching members, a latch member swiveled to one of said lateral members and disposed for engagement with the upper edges of the warp rest bars and the lower edges of the detector supporting bars, and a latch member pivoted to the free end of one of said lateral members and disposed for engagement with the upper edges of said detector supporting bars and for locking en-

gagement with the coöperating pivoted lateral member.

4. A latching device for removably locking the warp change mechanism of a loom in its frame, comprising a fixed member, a swiveled member, and a pivoted latch member, a mount for said swiveled and pivoted members and means for locking said pivoted member.

10 5. A latching device for removably locking the warp change mechanism of a loom in its frame comprising a pair of vertical members, a member connecting said vertical members, a member swiveled to one of said vertical members, and a latch member pivoted to one of said vertical members, and means for locking said pivoted member.

20 6. A latching device for removably locking the warp change mechanism of a loom in its frame comprising a pair of vertical members, a horizontal member rigidly connecting said vertical members, a laterally swingable member, and a vertically swingable member, and means for locking said vertically swingable member.

30 7. A latching device for removably locking the warp change mechanism of a loom in its frame comprising a pair of vertical pivoted members, a horizontal member rigidly connecting said vertical members, a laterally swingable member swiveled to one of said vertical members, and a vertically swingable member pivoted to one of said vertical members and adapted for locking engagement with the opposite vertical member.

40 8. In a warp stop motion, a frame, a warp change mechanism removably mounted therein and including a pair of spaced warp rest bars and a superimposed detector bar, and a latching device including a pair of members disposed on opposite sides of said warp change, a member connecting said pair of members and engaging said warp rest

45 bars, a swingable member pivoted to one of said pair of members and disposed between said warp rest and detector bars and a pivoted latch member engaging said detector bars, and means for locking said latch member.

50 9. In a warp stop motion, a frame, a warp change mechanism removably mounted therein and including spaced warp rest bars and detector bars, and a latching device including a pair of vertical members disposed on opposite sides of said warp change, a member rigidly connecting said vertical members and engaging the under sides of said warp rest bars, a laterally swingable member swiveled to one of said vertical members and engaging the upper sides of said warp rest bars and the under sides of said detector bars, a vertically swingable latch member pivoted to said vertical mem-

ber above said laterally swingable member 65 and engaging said detector bars on their upper sides, and means associated with said opposite vertical member for locking said latch member.

10. In a warp change mechanism, a frame, 70 a warp change removably mounted therein, and a latching device comprising a pair of pivoted vertical members, a swingable member pivoted to one of said vertical members, and engaging a part of said warp change 75 and a second swingable member pivoted to one of said vertical members and engaging another part of the warp change.

11. In a warp change mechanism, a frame, 80 a warp change mechanism therein, and a latching device including a pair of members pivoted to swing away from said warp change in opposite directions, a member engaging a part of said warp change and to which said pair of members are pivoted, a 85 member swingably connected to one of said pivoted members and engaging a part of said warp change, and means for locking said pivoted members in latching position.

12. In a warp change mechanism, a frame, 90 a warp change mechanism therein, and a latching device including a pair of members pivoted to swing away from said warp change in opposite directions, a member engaging a part of said warp change and to 95 which said pair of members are pivoted, a member disposed for engagement with a part of said warp change and having a connection with one of said pivoted members permitting partial turning movement thereof of about a horizontal axis and moving with said pivoted member in the swinging movements thereof, and means for locking said pivoted members in latching position. 100

13. In a warp change mechanism, a frame, 105 a warp change mechanism therein, and a latching device including a pair of members pivoted to swing away from said warp change in opposite directions, a rigid member engaging a part of said warp change 110 and to the opposite ends of which said pair of members are pivoted, a latch member pivoted to the free end of one of said opposed members, and means for locking said latch member in latching position. 115

14. In a warp change mechanism, a frame, a warp change removably mounted thereon, and a latching device including a pair of opposed members, one pivotally connected with said frame, a member having a connection with said pivoted member permitting movement therewith and capable of independent movement relative to said pivoted member and disposed for engagement with said warp change, and means for holding 120 said member in engagement with said warp change. 125

15. In a warp change mechanism, a frame,

2
a warp change removably mounted thereon, and a latching device including a member rigidly disposed across the warp change, a member pivoted to said rigid member, a member movable with said pivoted member and having a connection with said member permitting turning movement thereof about a horizontal axis, said last named member swingable transversely across the warp

change to lie in spaced relation to said rigid member, and means for holding the swingable member in said relation.

In testimony whereof I affix my signature in presence of two witnesses.

FRANCOIS D. RAYMOND.
